C. Dowdall Co.

UNITED STATES PATENT OFFICE.

THOMAS DOWDALL AND JOHN M. FENNERTY, OF VICKSBURG, MISS.

VENTILATOR.

SPECIFICATION forming part of Letters Patent No. 241,794, dated May 24, 1881.

Application filed March 9, 1881. (No model.)

To all whom it may concern:

Be it known that we, THOMAS DOWDALL and JOHN M. FENNERTY, of Vicksburg, in the county of Warren and State of Mississippi, have invented certain new and useful Improvements in Ventilators; and we do hereby declare that the following is a full, clear, and exact description of the invention, which will enable others skilled in the art to which it applies to make and use the same, reference being had to the accompanying drawings, which form a part of this specification.

Figure 1 is a vertical sectional view, and Fig. 2 is a top view.

Similar letters of reference indicate corresponding parts in both figures.

This invention relates to an improved ventilator, the construction and operation of which will be hereinafter more fully shown and described, and particularly pointed out in the claim.

In the drawings hereto annexed, A represents the base of our improved ventilator, which consists of a concavo-convex disk, capable of being secured, in any suitable manner, in the roof or ceiling of a room or apartment.

B is a pipe or tube extending upward from the base A and extending above the roof, where it is provided at some distance below its top or upper end with an annular flange or collar, C.

D is a tube, swiveled or journaled upon tube B, and having a flange, E, by which it rests upon the annular collar C, which forms a turn-table for the upper section of the ventilator. The tube D is provided with a conical deflector, F, connected, by rods G, with a ring, H, adjusted upon the tube B below the flange or turn-table C, so as to prevent displacement of the upper section of the ventilator.

Secured horizontally to the upper end of the vertical swiveled tube D is a tube, I, provided at one end with a funnel, J, and at the other

with a pair of wings or vanes, K. The latter serve to keep the funnel in the wind, and also 45 to balance it, thus causing the device to operate very easily. When a current of air enters the funnel J it passes through the tube I and over the tubes D B, in which a strong upward draft is thus created, the effect of 50 which is to carry off the foul and impure air from the room or apartment with which the ventilator is connected. The inclined sides of the funnel prevent the admission through the ventilator of any rain-water or other moisture 55 into the apartment. Smoke is also prevented from entering through the ventilator, inasmuch as the current merely passes through the funnel J and tube I and over the tubes D B, in which suction is thus created to carry off 60 foul air.

The deflector F, when arranged as shown, will prevent air and rain from entering through the turn-table joint.

This invention is simple, inexpensive, easily 65 applied or put in position, and it is automatic and effective in its operation.

Having thus described our invention, we claim and desire to secure by Letters Patent of the United States—

As an improvement in ventilators, the combination, with the base A, having tube B, provided with flange or collar C, of the swiveled tube D, having flange E, deflector F, ring H, and horizontal tube I, provided with the funnel J 75 and wings or vanes K, all arranged and operating substantially as herein described, for the purpose shown and specified.

In testimony that we claim the foregoing as our own we have hereto affixed our signatures 80 in presence of two witnesses.

THOMAS DOWDALL.
JOHN M. FENNERTY.
